(No Model.)

T. J. UNDERWOOD.

GRAIN ELEVATOR.

No. 377,917.

Patented Feb. 14, 1888.

UNITED STATES PATENT OFFICE.

THOMAS J. UNDERWOOD, OF DECATUR, ASSIGNOR OF ONE-HALF TO ELIAS DUNKEL, OF EMERY, ILLINOIS.

GRAIN-ELEVATOR.

SPECIFICATION forming part of Letters Patent No. 377,917, dated February 14, 1888.

Application filed May 12, 1887. Serial No. 238,003. (No model.)

To all whom it may concern:

Be it known that I, THOMAS J. UNDERWOOD, of the city of Decatur, county of Macon, and State of Illinois, have invented certain new and useful Improvements in Elevators for Grain, of which the following is a specification.

My invention consists in certain details of construction, combinations and sub-combinations, and relative arrangements of parts, as hereinafter set forth and claimed.

The device as a whole is particularly adapted for use in connection with a thrashing-machine, corn-sheller, or other analogous portable contrivance; but the buckets may be used in any place and under any circumstances that other buckets may be used.

In the drawings accompanying and forming a part of this specification, Figure 1 is a side view of my entire elevator, the casing being broken at top and bottom to show the inner mechanism. Fig. 2 is a side view of the upper portion of the elevator-casing. Fig. 3 is a perspective view of a belt-tightener that is peculiarly applicable to my device. Fig. 4 is a diagram of a clamp-bracket that provides shifting bearings for certain intermediate mechanism, hereinafter specified. Fig. 5 is a diagram of a portion of a clamp-hinge that adjustably and pivotally connects the elevator with the machine with which it may be co-operating. Fig. 6 is a face view of the hinge. Fig. 7 is a perspective view of my elevator-bucket. Fig. 8 is a perspective view of an inner corner of the bucket. Fig. 9 is an elevation of the outer surface of the bucket. Fig. 10 is a section of the bucket and the belt at a line coincident with the dotted line α in Fig. 9.

The elevator-casing 1 is preferably rectangular in cross-section, and, as a matter of convenience, it is usually inclined, as indicated in the drawings. On the top of the separator, corn-sheller, or other machine, as the case may be, is bolted a plate, 12, from which project upwardly the rounded bearings 11. Plates 8 and 10 are on opposite sides of the elevator and are held in position by clamping-bolts 9. On plate 8 are undercut projections 7, that rest on bearings 11 and support the elevator in a manner permitting pivotal adjustment. The web 24 (seen in Fig. 6) extends above the

bearings 11 and prevents lateral disadjustment of the hinge.

Bracket-plate 14 and brace-bar 21 are on opposite sides of the elevator and are clamped thereon in any desired position by bolts 22. Brackets 16 form bearings for the shaft of bevel-pinion 17 and sprocket-wheel 20. Pintle 23 provides a bearing for the combined bevel-gear and sprocket-wheel 18 19. Slots 15 in plates 14 and 21 permit the clamping-bolts to be shifted laterally to conform to variations caused by placing the plates more or less obliquely across the elevator, the object being to keep the bolts close to the elevator under all circumstances of adjustment.

The shafts of pulleys 26 and 27 are each mounted in sliding frames or belt-tighteners, as indicated in Fig. 2 and shown in detail in Fig. 3. A stationary frame is composed of 70 side bars, 28, and cross-bars 29 30, and cross-bar 29 is provided with threaded head 34. A sliding plate, 31, is placed between the side bars and behind the cross-bars of the stationary frame and is provided with bearing 32 and 75 head 33. The side bars, 28, are secured to the elevator-frame, and a threaded bolt, 35, in head 34 presses against head 33 and provides means for regulating the vertical position of the sliding plate.

The belt 4 has buckets that are composed each of a curved outer plate, 5, of scoop formation, end pieces, 36, and fingers 37, and that are secured to the belt at the lower termination of the scoop-plate. The means preferably employed for securing the buckets to the belt comprise the bolts 40, (shown in Fig. 10,) and in order that said bolts may be in line with the lower termination of the scoop-plate cavities 38 are formed therein and perforated 90 at 39 to receive the bolts. The belt is slightly wider than the buckets, and the fingers hold the ends of the scoops in close contact with the belt while the same is straight. When a pulley is reached, the belt curves away from the 95 scoop portion of the bucket and gives the same a chance to fill or discharge, as the case may be.

The sprocket-chain 13 is intended to connect with a sprocket-wheel occupying a stated position on the machine to which the elevator is attached and receiving motion therefrom,

and the clamp-bracket may be raised or lowered and set more or less obliquely in order to place the sprocket-wheel 20 in proper alignment. The chain 43 conveys motion from 5 sprocket-wheel 19 to a sprocket-wheel, 25, in Fig. 2, which is on the outer end of the shaft of wheel 26. If, when the chains and belt are in position, the belt should need tightening, then the lower pulley-shaft should be forced 10 downward by the shifting mechanism shown in Fig. 3. Should the belt be tight and the chains too loose, then the belt and both belt-pulleys are carried upward to the required extent by the said shifting mechanism, and 15 the clamp-bracket is adjusted to equalize the strain on chains 13 and 43.

The grain is fed to the bottom of the elevator in the direction indicated by arrow 42, and the receptacle 2 permits the accumulation of 20 a quantity of grain sufficient to equalize the supply and insure a steady and uniform load to the elevator-buckets. A lid, preferably sliding, as shown at 6 in Fig. 1, gives access to the belt and to the compartment 2.

25 The arrow 41 indicates the point of view from which, on Fig. 1, the representation of the hinge shown in Fig. 6 is taken.

The hinge attachment permits the elevator to be attached to variously-inclined surfaces, 30 and is a convenience in obviating the necessity of leveling the machine before making the attachment.

The buckets may be placed at any desired distance apart on the belt, and may be secured to said belt in any suitable manner, the only 35 essential requirement in this regard being that the connection shall be made at the lower termination of the scoop portion.

I claim as new and desire to secure by Letters Patent—

40 1. The bucket having back and sides, the downward extensions 37, and the perforated cavities 38, as and for the purpose set forth.

2. The bucket having back and sides, the downward extensions 37, and means at the 45 lower termination of the bucket for securing the same to a belt, as and for the purpose set forth.

3. The elevator-casing, the belt-pulleys provided each with bearings adapted to be shifted, 50 the adjustable clamp-bracket carrying the gearing, the main sprocket-chain, the secondary sprocket-chain, and the sprocket-wheel on the shaft of the upper belt-pulley, all in combination, as and for the purpose set forth. 55

4. The hinge-clamp 7 8 9 10 and the coacting plate 12, with the bearings 11 and the web 24, as and for the purpose set forth.

THOMAS J. UNDERWOOD.
